J. C. McLACHLAN,

MOLD FOR CASTING SHELLS,

APPLICATION FILED OCT. 18, 1915. RENEWED DEC. 22, 1916.

1,215,564.

Patented Feb. 13, 1917.

Inventor.

John Campbell McLachlan
by A. J. S. Dennis, Atty.

UNITED STATES PATENT OFFICE.

JOHN C. McLACHLAN, OF TORONTO, ONTARIO, CANADA.

MOLD FOR CASTING SHELLS.

1,215,564.

Specification of Letters Patent.

Patented Feb. 13, 1917.

Application filed October 18, 1915, Serial No. 56,365. Renewed December 22, 1916. Serial No. 138,492.

To all whom it may concern:

Be it known that I, JOHN CAMPBELL McLACHLAN, a subject of the King of Great Britain, and resident of the city of Toronto, county of York, Province of Ontario, in the Dominion of Canada, have invented certain new and useful Improvements in Molds for Casting Shells, as described in the following specification and illustrated in the accompanying drawings, that form part of the same.

The objects of the invention are, to effect a material reduction in the cost of manufacturing shrapnel, or other explosive shells, and to produce by a casting process a shell having all the requirements of hardness, smoothness of surface and accuracy of weight and balance.

A further object is to obtain greater and quicker production of explosive war munitions.

The principal feature of the invention consists in the novel construction of a mold and the method of casting the shell, whereby the shell is completed and requires practically no machining after its removal from the mold.

In the drawings, Figure 1 represents a vertical elevational view of a mold used in constructing shells in accordance with this invention, one-half being in longitudinal section.

Fig. 2 is a partial top plan view.

Fig. 3 is a partial section taken horizontally through the line *a*—*b* of Fig. 1.

Like numerals of reference indicate corresponding parts in each figure.

In carrying this invention into effect it is intended to cast the body of the shell in a chill mold, thus producing a smooth, accurate and uniform surface for contact with the inner bore of the gun from which it is to be fired. The mold consists of a circular-shaped base 1 having a central circular boss 2 formed thereon and provided with a centrally arranged cylindrical opening 3.

4 are the chill sections comprising a pair of half round members each formed with a flange 5 to rest upon the base 1 and a recess 6 to receive the boss 2. The outer walls of the chills are formed with a plurality of circumferentially arranged ribs 7 which disperse the heat quickly and effect rapid cooling of the cast member. The upper ends of the chill sections are formed

with an enlarged annular recess 8 adapted to receive the head block 9 which is secured in position by means of the fastening ring 10 which is held by suitable clamps not shown.

The head 9 is provided with openings 11 and 12 forming the pouring entrance and gas vents respectively.

13 is an annular recess formed in the inner wall of the chills adjacent to the upper end and in which is placed a dry sand core 14 adapted to form a dove-tailed shaped groove in the external surface of the shell. This groove is vented by means of the holes 13a.

15 is a tubular perforated core center extending through the cylindrical opening 3 and rigidly supported in central alinement within the mold formed by the chills 4. 75 This tube is shown with a rounded upper end 16 perforated and an open bottom end 17. Around the core center 15 is formed a dry sand core 18 which is shaped externally to the exact inner shape of the shell 80 to be cast.

19 is a sleeve fitted into the opening 3 in the base and surrounding the core center 15 and forming a rigid support for same, the upper end thereof abutting a ring 21 85 on the core center.

The sleeve and core center are locked in position by a key 22 or other suitable fastening engaging the lower end of the core center which extends through the base. 90

The end of the sleeve 19 extending above the base is threaded externally to form a chill surface for the threaded central opening of the shell and the sleeve is separable from the base so that it can be readily unscrewed from the shell when cast, the thread being coated with a thin coat of tar and plumbago.

The semi-cylindrical chill members 4 which are provided with radial edge flanges 100 adapted to fit snugly together and held in register by suitable dowel pins 20 are fastened together by any suitable form of clamps which are not here shown.

In carrying out the manufacture of shells 105 according to this invention the molds are set up in the manner shown and as the metal is poured, the exterior of the shell is at once chilled by contact with the outer metal case. The interior wall of the mold is coated with 110 a thin coating of tar and plumbago which prevents the metal sticking to the sides of

the mold and also insures its free and uniform flow to form a very closely grained and dense surface free from defects. The central dry sand core allows the escape of gases generated within the mold to the perforated core center 15 and these are rapidly dissipated without creating internal pressures and thus allow the metal as poured to form into a uniformly dense mass throughout the entire mold, preserving the proper balance of the shell and insuring a dense and hard grain which is extremely desirable in the production of shells. The mold can be opened practically immediately following the pouring and consequently the chills will be allowed to cool very quickly and be ready for further use.

The threaded sleeves 19 may be readily removed from the base and renewed as desired.

A shell cast in the manner described fulfills all requirements and requires no finishing other than to clean out the thread and apply the copper gas ring to the dove-tailed recess. The cost of manufacture is thus reduced to the minimum and rapidity of production is assured.

What I claim as my invention is:—

1. A shell mold, comprising, a rigid base having a central opening, a sectional chill forming the outer wall of the mold adapted to be centered upon and removably secured to said base, a hollow perforate core center centered in the opening in said base and provided with a projecting shoulder forming a support for the core, means engaging the lower end of said core center and adapt-

ed to clamp same rigidly to said base to rigidly support same axially within the mold, and a head block closing the top of the mold and having pouring and overflow vents.

2. A shell mold comprising, a base having a central opening, a sectional chill adapted to be centered upon and removably secured to said base to form a mold, a sleeve centered in the opening in said base and extending upwardly therefrom and having a threaded exterior forming the inner wall of the lower part of the mold, and a perforate core center rigidly supported in said sleeve and extending upwardly into the mold.

3. A shell mold, comprising, a base having a central opening, a sleeve fitted in said opening and extending perpendicularly upward from said base, said sleeve having a threaded exterior, a perforate tube extending through said sleeve and having a ring resting upon the upper end of said sleeve, means connected to the bottom of said perforate tube for locking said tube and sleeve in said base, a sand core encircling said perforate tube, and a sectional chill centered upon said base and surrounding said core and having pouring and vent openings at the top.

Signed at the city of Toronto, county of York, Province of Ontario, in the Dominion of Canada, this 13th day of October 1915.

J. C. McLACHLAN.
